UNITED STATES PATENT OFFICE.

RICHARD D. MARTIN, OF LAS ESPERANZAS, MEXICO.

DRAWING-MACHINE FOR COKE-OVENS.

No. 818,841.

Specification of Letters Patent.

Patented April 24, 1906.

Application filed March 2, 1905. Serial No. 248,186.

To all whom it may concern:

Be it known that I, RICHARD DANIEL MARTIN, a citizen of the United States, and a resident of Las Esperanzas, Coahuila, Mexico, have invented a new and Improved Drawing-Machine for Coke-Ovens, of which the following is a full, clear, and exact description.

The invention relates to drawing-machines for coke-ovens, such as shown and described in the Letters Patent of the United States No. 681,064, granted to me August 20, 1901.

The object of the present invention is to provide a new and improved drawing-machine which is simple and durable in construction, very effective in operation, and arranged to allow convenient manipulation of the machine through the small door of the coke-oven, and to permit discharging the coke from the oven underneath the machine without interference with the working parts of the machine.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is an end elevation of the improvement as applied to a coke-oven, shown in cross-section. Fig. 2 is a plan view of the same, the coke-oven being shown in section. Fig. 3 is an enlarged end view of the machine, parts being broken out. Fig. 4 is a section on the line 4 4 of Fig. 3. Fig. 5 is an enlarged plan view on the line 5 5 of Fig. 1 of the mechanism for imparting a traveling motion to the scraper-beam. Fig. 6 is an enlarged end elevation of the mechanism for imparting an up-and-down swinging motion to the scraper, parts being shown in section. Fig. 7 is a section on the line 7 7 of Fig. 4, and Fig. 8 is a section on the line 8 8 of Fig. 1.

The improved drawing-machine is preferably mounted on a flat railroad-car A, mounted to travel on rails B, arranged in front of a coke-oven C, from which the products are removed at the proper time by a scraper D through a coke-oven door-casing C' over a chute E into a conveyer F, mounted on the railroad-car A and discharging into a second conveyer F', arranged at right angles to the

conveyer F and having its delivery end so arranged as to discharge the coke to one side of the machine alongside the railroad-bed.

The scraper D consists, essentially, of a guideway D', in which is mounted to travel lengthwise a scraper-beam D², carrying at its forward end a number of scraper-blades D³, D⁴, and D⁵, arranged one in front of the other and fulcrumed on the beam D² in such a manner that the blades are free to swing when the beam moves inwardly in the oven, so that the blades ride over the coke, and when the beam D² moves outward the said scraper-blades D³, D⁴, and D⁵ are held in an angular position relative to the scraper-beam D² (see Fig. 1) to cause the said scraper-blades to move the coke outwardly toward the door-casing C', the outward movement of the scraper-beam D² being sufficient for the scraper-blades D⁵ and D⁴ to pass practically out of the door-casing C' to push the coke over the chute E onto the conveyer F, while the other scraper-blade D³ remains within the oven.

In order to impart the desired traveling motion to the scraper-beam D² on its guideway D', an endless sprocket-chain G is provided, extending lengthwise on the guideway D' and passing over sprocket-wheels G' and G², journaled in the ends of the guideway D', the sprocket-wheel G² having its shaft G³ driven, as hereinafter more fully described, the said sprocket-chain being engaged at one of its links in the lower run by a lug or pin D⁶, projecting upwardly from the scraper-beam D². (See Fig. 4.) When a traveling motion is given to the sprocket-chain G, then the link engaging the lug or pin D⁶ causes a forward or backward traveling motion of the scraper-beam D² in its guideway D', according to the direction in which the sprocket-chain G is caused to travel at the time.

The guideway D' is fulcrumed loosely at or near its middle on a transverse shaft H, (see Figs. 1, 3, 4, and 5,) journaled in the arms of a fork I', depending from a swivel I, mounted to turn on the lower end J' of a support J, attached to braces J², depending from a carriage K, mounted to travel forward and backward on a track L, preferably formed of channel-beams and secured to an overhead structure A', forming part of the railroad-car A. The carriage K is held against tipping on the track L, and for this purpose the carriage

is provided with angle-irons K' and K^2 , engaging the top and bottom flanges L' and L^2 of the channel-irons forming the track L . (See Fig. 4.) In order to allow an easy traveling of the carriage K on the track L , the carriage is provided with friction-rollers K^3 , traveling on the upper surfaces of the flanges L' of the track L .

A forward and backward traveling motion is given to the carriage K , so as to move the scraper in and out of the oven C . For this purpose the carriage K is provided on its top with a nut K^4 , in which screws a screw-rod N , mounted to turn in a suitable bearing L^3 , carried by the track L , (see Figs. 1 and 2,) and on the said screw-rod N (see Fig. 8) is secured a spur-wheel N' in mesh on opposite sides with gear-wheels O and O' , journaled on a lever O^2 , fulcrumed loosely on the screw-rod N , the said lever O^2 having a locking device O^3 adapted to engage one of a series of notches on a segment O^4 , attached to the track L . The gear-wheel O is an intermediate gear-wheel and is in mesh with a gear-wheel O^5 , likewise journaled on the lever O^2 , and the gear-wheels O' and O^5 are adapted to mesh with opposite sides of a gear-wheel P' , secured on a driven shaft P , journaled in suitable bearings L^4 and L^5 in the ends of the track L . (See Figs. 3 and 8.) On the shaft P is secured a sprocket-wheel P^2 , connected by a sprocket-chain P^3 with a sprocket-wheel P^4 , secured on the shaft Q' of a motor or engine Q of any approved construction and mounted on the flat railroad-car A . When the engine or motor Q is started, a rotary motion is transmitted by the sprocket-wheels P^4 and P^2 and the sprocket-chain P^3 to the shaft P , which imparts a turning motion to the screw-rod N in either a forward or backward direction, according to which of the two gear-wheels O' or O^5 is in mesh at the time with the gear-wheel P' , secured on the driven shaft P . When the screw-rod N is driven in one direction, the nut K^4 travels from the right to the left, thus moving the carriage K , swivel I , and scraper D in a like direction—that is, moving the scraper D into an operative position—and when the screw-rod N is turned in a reverse direction then the carriage K is caused to travel from the left to the right, and with it the swivel I and the scraper D , to move the latter out of the oven and into an inactive position.

It is understood that in order to reverse the motion of the screw-rod N it is only necessary for the operator to unlock the lever O^2 and then impart a swinging motion to the same, so as to move either the gear-wheel O' or the gear-wheel O^5 in mesh with the gear-wheel P' , rotating at the time. When the carriage K reaches its extreme position either to the left or to the right, then the operator swings the lever O^2 into an intermediate position to hold both gear-wheels O' and O^5 out

of mesh with the gear-wheel P' , so that the screw-rod N is at a standstill, while the shaft P may be still driven from the motor Q .

A traveling motion is given to the shaft G^3 of the sprocket-wheel G^2 , employed for driving the chain G either forward or backward, with a view to move the scraper-beam D^2 , as previously described, and for this purpose the following device is provided: On the shaft G^3 (see Fig. 5) is secured a bevel gear-wheel G^4 in mesh with a bevel-pinion R' , connected by a key and keyway with a shaft R , journaled in suitable bearings R^2 and R^3 , carried by one side of the guideway D' , and on the said shaft R is secured another bevel-pinion R^4 , in mesh with a double-bevel gear-wheel H' , secured on the shaft H , on which the scraper-guideway D' is mounted to swing loosely as a fulcrum. The bevel gear-wheel H' is in mesh with a bevel gear-wheel H^2 , secured on the lower end of a vertically-disposed shaft H^3 , journaled in the support J , on which the swivel I is mounted to turn, it being understood that the axis of the said shaft H^3 and that of the swivel I coincide, the coinciding axis being disposed vertically. On the upper end of the shaft H^3 is secured a bevel gear-wheel H^4 , adapted to be engaged on opposite sides by either a bevel gear-wheel S or S' , having a common hub S^2 , connected by key and keyway with the shaft P , so that when the latter is driven from the motor Q , as previously described, then the gear-wheel S or S' , in mesh with the bevel gear-wheel H^4 , imparts a rotary motion to the shaft H^3 , and as the latter is connected by the gear-wheels H^2 and H' with the shaft H it is evident that the latter is rotated, and the rotary motion of this shaft H is transmitted by the bevel gear-wheel H' and pinion R^4 , shaft R , pinion R' , and gear-wheel G^4 to the shaft G^3 to rotate the sprocket-wheel G^2 with a view to impart a traveling motion to the sprocket-chain G in either direction—that is, according to which of the bevel gear-wheels S or S' is in engagement with the bevel gear-wheel H^4 at the time.

The connected gear-wheels S and S' are connected at their hub with a shifting-lever S^3 , fulcrumed on the support J^2 and under the control of the operator, the shifting-lever S^3 being normally locked in either of its two positions by a suitable locking-arm S^4 , having notches S^5 and S^6 for engaging a pin S^7 on the shifting-lever S^3 . When the bevel gear-wheel S is in mesh with the bevel gear-wheel H^4 , as shown in Fig. 3, then the pin S^7 is engaged by the notch S^5 , and when the bevel gear-wheel S' is in mesh with the bevel gear-wheel H^4 then the pin S^7 is engaged by the notch S^6 . Thus in either position the shifting-lever S^3 is held in a locked position to hold the corresponding bevel gear-wheel S or S' in mesh with the bevel gear-wheel H^4 . The lever S^3 may be moved to an inactive

position, so that neither of the bevel gear-wheels S or S' is in mesh with the bevel gear-wheel H⁴.

By mounting the scraper-guideway D' on the swivel I the scraper can be turned laterally in any desired direction, so as to permit of reaching with the scraper-blades every part in the oven C, it being understood that after the scraper-guideway D' has been swung laterally into the desired position it is locked therein during the time the scraper-blades are active—that is, moved inward and outward with the scraper-beam D² to move the coke through the coke-oven casing C' and over the chute E, as previously mentioned.

In order to lock the scraper-guideway in position against sidewise swinging, the following device is provided: On the swivel I is secured a quadrant T, adapted to be engaged at any one of its notches by a projection T', formed on a lever T² under the control of the operator and fulcrumed at T³ on the support J. When the operator swings the lever T² upwardly to disengage the lug T' from one of the notches in the quadrant T, then the swivel I is unlocked to allow turning of the swivel to swing the scraper laterally until the desired position is reached, and then the operator swings the lever T² downward to engage the lug T' with the corresponding registering notch of the quadrant T to lock the swivel I against turning for the time being.

Normally the scraper-guideway D' is held in an approximately horizontal position, and for this purpose flexible connections U and U' are provided, extending from opposite sides of the swivel I to connect with the scraper-guideway D' on opposite sides of its fulcrum on the shaft H. (See Fig. 3.) Each of the flexible connections U and U' consists, preferably, of a chain U² and a spring U³, and one end of the chain U² is connected with the scraper-guideway D', and the other end of the chain is connected with one end of the spring U³, attached at its other end to the swivel I. By the arrangement described the guideway D' is normally supported in a horizontal position; but the flexible connections allow up-and-down swinging of the guideway to bring the scraper-blades D³, D⁴, and D⁵ into proper position relative to the coke in the oven C.

In order to impart the up-and-down swinging motion to the scraper D, the following device is provided: On the shaft H (see Figs. 5 and 6) is secured a brake-wheel V, engaged by a brake-band V', secured at one end at V² to one side of the scraper-guideway D', the other end of the said brake-band V' being pivotally connected with a sliding nut V³, having a polygonal external shape and mounted to slide in a bearing V⁴, secured to the guideway D'. In the sliding nut V³ screws the threaded end V⁵ of a rod V⁶, having its other end V⁷ threaded in an opposite

direction to the threads on the nut V⁵, and the outer end V⁷ screws in a nut V⁸, attached to the guideway D'. On the rod V⁶ is secured a collar V⁹, having apertures in its periphery for the insertion of a suitable tool to permit the operator to conveniently turn this rod V⁶ so as to screw the rod either forward or backward in the nut V⁸, it being understood that said movement of the rod V⁶ causes a forward or backward sliding of the nut V⁸ and its bearing V⁴ to apply the brake-band V' with more or less force on the peripheral surface of the brake-wheel V. When the brake-band V' is in frictional contact with the brake-wheel V and the shaft H is rotated in a forward direction for moving the scraper-beam D² inward in the oven C, then the brake-wheel V is rotated, and with it the band V', so that the latter exerts a pull on the nut V⁸, and as the latter is held on the guideway D' it is evident that a swinging motion is given to the guideway D' to raise the forward end thereof, and with it the scraper-beam D' and the scraper-blades D³, D⁴, and D⁵. Thus the scraper-blades while traveling inward glide over the coke, and when the motion of the shaft H is reversed and the scraper-beam D² is caused to travel outward then the swinging motion of the guideway D is reversed—that is, its forward end swings downward—so as to bring the scraper-blades D³, D⁴, and D⁵ in engagement with the coke to rake the same forwardly toward the oven-casing C' and to finally push the coke through the said casing over the chute E onto the first conveyor F.

By the operator adjusting the rod V⁶ all wear between the brake-band V' and the brake-wheel V can be taken up to insure a proper automatic swinging of the scraper-guideway D' in the manner above described.

In order to take up any undue slack in the chain G, employed for imparting a reciprocating motion to the scraper-beam D², the shaft G³ is mounted in bearings G⁵ and G⁶, mounted to slide lengthwise in the sides of the scraper-guideway D', (see Figs. 1 and 5,) the said bearings G⁵ and G⁶ being held adjustable by suitable adjusting-screws G⁷. The bearing R², previously mentioned, forms part of the bearing G⁵, (see Fig. 5,) and the bevel gear-wheel R' is mounted to turn with and to slide on the shaft R to allow adjustment of the bearings G⁵ and G⁶ without disconnecting the bevel gear-wheels G⁴ and R'. 115

The conveyors F and F' are preferably of the endless metallic slat-belt type and are driven by suitable gearing from the motor Q, (see Figs. 1 and 2;) but as the detail construction of the said conveyors and the mode of driving the same is not a part of this invention further description of the same is not deemed necessary.

The operation is as follows: When the machine is not in use, then the scraper-beam D² 130

is in a right-hand end position in the guideway D' and the latter is in a right-hand end position, so that the left-hand end of the guideway D' is within the corresponding side 5 of the car A to permit of conveniently moving the latter along the rails B to bring the machine in front of the oven C, from which the coke is to be drawn. In order to do this, the chute E is placed in position so as to connect the oven-door casing C' with the conveyer F, and then the motor Q is started to rotate the shaft P, which latter by the gear-wheels P', O⁵, O, and N' rotates the screw-rod N to move the carriage K from its right- 10 hand position to a left-hand position along the track L. In doing so the scraper D is carried bodily along, and consequently the left-hand end of the scraper-guideway D' is projected through the oven-door casing C' 15 into the oven, as indicated in Fig. 1. When this position is reached, the lever O² is thrown into an intermediate position to disconnect the screw-rod N from the shaft P to stop the rotation of the said screw-rod. The operator 20 now swings the lever S² into an active position to engage the bevel gear-wheel S with the bevel gear-wheel H⁴ to rotate the shaft H³, which by its connection with the shaft G³, as previously described, causes a 25 traveling of the sprocket-chain G to slide the scraper-beam D² from the right to the left along the guideway D', and at the same time a tilting motion is given to the guideway D by the brake device previously described, so that the scraper-blades D³, D⁴, and D⁵ glide 30 readily over the coke during the inward travel of the beam D² in the oven C. When an innermost position is reached by the scraper-blades D³, D⁴, and D⁵, then the operator reverses 35 the lever S², so as to throw the bevel gear-wheel S out of mesh with the bevel gear-wheel H⁴ and to move the bevel gear-wheel S' into mesh with the bevel gear-wheel H⁴. The traveling motion of the chain G is now 40 reversed and likewise that of the scraper-beam D², and the tilting of the guideway D' is reversed, so that the scraper-blades D³, D⁴, and D⁵ move downward in contact with the coke 45 and at the same time travel outwardly to draw the coke toward the oven-door casing C' and finally over the chute E to the endless conveyer F, which in turn delivers the material to the conveyer F', and the latter discharges the same to one side of the machine. When 50 the scraper-blades D³, D⁴, and D⁵ reach an outermost position, as previously mentioned, then the operator reverses the lever S² to move the bevel gear-wheel S' out of mesh with the bevel gear-wheel H⁴ and to move the bevel gear-wheel S in mesh with the bevel gear-wheel H⁴, and then the above-described 55 operation is repeated—that is, more coke is raked outwardly, but along the same line. After the coke has been removed along this 60 line of movement the operator unlocks the 65

swivel I by swinging the lever T² upwardly, and then the operator swings the scraper D laterally to the desired position, after which the swivel I is again locked in place by the lever T². The above-described operation of imparting movement to the beam D² and tilting the guideway D' is then repeated, so that the beam D² works in the oven along another line of movement, and in this manner the entire oven may be drawn clear of the coke, as 70 each and every part within the oven can be reached by proper adjustment of the swivel I and movement of the beam D², as above described. 75

It is understood that when the tilting movement is given to the guideway D' then one of the flexible connections U or U' is put under tension, while the other is slack, the tension of the spring U³ of the corresponding flexible connection put under tension at the 80 time being governed by the action of the tilting device—that is, by the frictional contact between the brake-band V' and the brake-wheel V. 85

Instead of the reversing-gearing S, S', and 90 H⁴ the shaft H³ may be reversed by reversing the motor every time the scraper-beam reaches its extreme inward or outward position. In this case the bevel gear-wheel S' is dispensed with and only the bevel gear-wheel 95 S is used and thrown out of mesh with the bevel gear-wheel H⁴ by the shifting-lever S³ whenever the carriage K is shifted from an inactive to an active position, or vice versa, on shifting the lever O², as previously mentioned. 100

It will be evident from the description that when motion is imparted to the scraper to move it into the oven the first action of the shaft H will be to tighten the brake, which 105 will elevate the guideway and the scraper. The provision of the chains v² prevents undue lifting of the scraper, such lifting merely being sufficient to carry the scraper above the coke. When the rear end of the oven is 110 reached, a reverse movement of the shaft H immediately swings the scraper downward into contact with the coke. 115

Having thus described my invention, I claim as new and desire to secure by Letters Patent—

1. In a drawing-machine, the combination of a trackway, a carriage upon the trackway, a swivel supported by the carriage, a guideway mounted to swing up and down on the 120 swivel, means for limiting the swinging movement of the guideway with respect to the swivel, a scraper-beam slidably mounted on the guideway, a scraper on the scraper-beam, means for moving the scraper-beam longitudinally of the guideway, and means whereby movement of the beam in one direction may swing the guideway downward and whereby movement in the opposite direction may swing the guideway upward. 125 130

2. A drawing-machine having a scraper, a shaft on which the scraper is fulcrumed to swing up and down, a swivel carrying the said shaft, and a carriage mounted to travel forward and backward, to move the scraper in and out of an operative position.

3. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, and means whereby the travel of the scraper-beam may swing the guideway.

4. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, means for imparting a reciprocating motion to the said scraper-beam in its guideway, and means whereby the reciprocation of the scraper-beam may swing the guideway.

5. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, means for imparting a reciprocating motion to the said scraper-beam in its guideway, the said means comprising an endless sprocket-chain mounted to travel on the said scraper-guideway and connected with the said scraper-beam and a driving-gear for the said sprocket-chain, having a portion extending through the said swivel, and means whereby the reciprocation of the scraper-beam may swing the guideway.

6. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, means for imparting a reciprocating motion to the said scraper-beam in its guideway, the said means comprising an endless sprocket-chain, sprocket-wheels journaled on the said guideway and over which passes the said sprocket-chain, a longitudinal shaft journaled on the said guideway, gear-wheels connecting the said longitudinal shaft with one of the said sprocket-wheels, a transverse shaft journaled in the said swivel and on which the said guideway is mounted to swing up and down, a gearing connecting the said longitudinal shaft with the said transverse shaft, a vertically-disposed shaft having its axis coinciding with that of the swivel, and a gearing

connecting the said transverse shaft with the said vertically-disposed shaft.

7. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, means for imparting a reciprocating motion to the said scraper-beam in its guideway, the said means comprising an endless sprocket-chain, sprocket-wheels journaled on the said guideway and over which passes the said sprocket-chain, a longitudinal shaft journaled on the said guideway, gear-wheels connecting the said longitudinal shaft with one of the said sprocket-wheels, a transverse shaft journaled in the said swivel and on which the said guideway is mounted to swing up and down, a gearing connecting the said longitudinal shaft with the said transverse shaft, a vertically-disposed shaft having its axis coinciding with that of the swivel, a gearing connecting the said transverse shaft with the said vertically-disposed shaft, a main driven shaft, and a manually-controlled gearing connecting and disconnecting the said main driven shaft with and from the said vertically-disposed shaft.

8. In a drawing-machine, the combination of a carriage, a swivel supported by the carriage, a guideway mounted to swing up and down on the swivel, means for limiting the swinging movement of the guideway, a scraper slidably mounted on the guideway, means for moving the scraper longitudinally of the guideway, and means whereby movement of the scraper in one direction may swing the guideway downward, and whereby movement in the opposite direction may swing the guideway upward.

9. In a drawing-machine, the combination of a swivel, a guideway mounted to swing up and down on the swivel, means for limiting the swinging movement of the guideway, a scraper slidably mounted on the guideway, means for moving the scraper longitudinally of the guideway, and means whereby movement of the scraper may impart a swinging motion to the guideway.

10. A drawing-machine having a scraper, a support, a swivel mounted to turn on the said support, the axis of the swivel being disposed vertically and the said scraper being mounted to swing up and down on the said swivel, a carriage carrying the said support, an overhead guideway for the said carriage to travel on, and means for imparting forward and backward motion to the said carriage.

11. In a drawing-machine, the combination of a swivel, a scraper mounted to swing up and down on the swivel, means for limiting the swinging motion of the scraper,

means for moving the scraper longitudinally with respect to the swivel, and means whereby the longitudinal movement may swing the scraper.

5 12. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, and means whereby the travel of the scraper-beam may impart an up-and-down swinging motion to the said scraper-guideway.

15 13. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, means for imparting an up-and-down swinging motion to the said scraper-guideway, the said means comprising a revolute shaft journaled in the said swivel and forming the fulcrum for the said guideway, a brake-wheel secured on the said shaft, a brake-band for the said brake-wheel, having one end fixed on the said guideway, and means under the control of the operator 25 and connected with the other end of the said brake-band, for adjusting the tension of the band.

35 14. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, means for imparting an up-and-down swinging motion to the said scraper-guideway, the said means comprising a revolute shaft journaled in the said swivel and forming the fulcrum for the said guideway, a brake-wheel secured on the said shaft, a brake-band for the said brake-wheel, having one end fixed on the said guideway, a sliding nut on the said guideway, connected with the other end of the said brake-band, a screw-rod having right and left hand screw-threads, of which one screws in the said sliding nut, and a nut fixed on the said guideway and in which screws the other screw-thread of the said screw-rod.

45 15. A drawing-machine having a scraper provided with a guideway, a scraper-beam mounted to travel on the said guideway, a scraper-blade on the scraper-beam, a swivel on which the scraper-guideway is fulcrumed to swing up and down, the axis of the swivel being disposed vertically, means for imparting an up-and-down swinging motion to the said scraper-guideway, the said means comprising a revolute shaft journaled in the said swivel and forming the fulcrum for the said

guideway, a brake-wheel secured on the said shaft, a brake-band for the said brake-wheel, having one end fixed on the said guideway, a sliding nut on the said guideway, connected with the other end of the said brake-band, a screw-rod having right and left hand screw-threads, of which one screws in the said sliding nut, a nut fixed on the said guideway and in which screws the other screw-thread of the said screw-rod, and means on the screw-rod for allowing the operator to turn the same.

75 16. A drawing-machine having a scraper, a support, a swivel mounted to turn on the said support, the axis of the swivel being disposed vertically and the said scraper being mounted to swing up and down on the said swivel, manually-controlled means for locking the said swivel to the said support, means for moving the scraper longitudinally with respect to the swivel, and means whereby said longitudinal movement may swing the 80 scraper.

85 17. A drawing-machine having a scraper, a swivel on which the scraper is mounted to swing up and down, the axis of the swivel being disposed vertically, and flexible and extensible connections between the swivel and the scraper, to hold the scraper approximately in a horizontal position and to allow up-and-down movement thereof.

90 18. A drawing-machine having a scraper, a swivel on which the scraper is mounted to swing up and down, the axis of the swivel being disposed vertically, and flexible connections between the swivel and the scraper, to hold the scraper approximately in a horizontal 100 position and to allow up-and-down movement thereof, each connection consisting of a chain and a spring.

95 19. A drawing-machine having a scraper, a swivel on which the scraper is mounted to swing up and down, the axis of the swivel being disposed vertically, and flexible connections between the swivel and the scraper, to hold the scraper approximately in a horizontal 110 position and to allow up-and-down movement thereof, each connection consisting of a chain connected at one end to the scraper and a spring connected at one end to the chain and at the other end to the swivel.

115 20. A drawing-machine having a scraper, a swivel on which the scraper is mounted to swing up and down, the axis of the swivel being disposed vertically, flexible connections extending obliquely from opposite sides of the swivel, to connect with the said scraper on opposite sides of its fulcrum, means for moving the scraper longitudinally of the swivel, and means whereby the longitudinal movement may swing the scraper.

120 21. A drawing device comprising a scraper, a swivel on which the said scraper is mounted to swing up and down, a carriage mounted to travel and on which the swivel is mounted to

turn on a vertical axis, a screw-rod screwing in the said carriage and extending in the direction of the travel of the carriage, a driven shaft, and a manually-controlled reversing-
5 gear for connecting the said driven shaft with the said screw - rod, to rotate the latter in either direction.

In testimony whereof I have signed my name to this specification in the presence of two subscribing witnesses.

RICHARD D. MARTIN.
